UNITED STATES PATENT OFFICE.

OTTO MALCHER, OF CHICAGO, ILLINOIS, ASSIGNOR TO CARLIN CALCULATOR CO., OF CHICAGO, ILLINOIS, A CORPORATION OF ILLINOIS.

CALCULATING-MACHINE.

1,120,318.

Specification of Letters Patent.

Patented Dec. 8, 1914.

Application filed July 13, 1911, Serial No. 638,277. Renewed May 4, 1914. Serial No. 836,358.

To all whom it may concern:

Be it known that I, OTTO MALCHER, a citizen of the United States, residing at Chicago, in the county of Cook and State 5 of Illinois, have invented certain new and useful improvements in Calculating-Machines, of which the following is a specification.

This invention relates in general to calculating machines of the type in which there is employed a register embodying a plurality of rotatable number bearing members or wheels upon which the amounts are registered, the members being controlled by 10 individual selecting mechanisms whereby they may be sent for variable movement by a driving mechanism which is under the control of the operator through the agency of a suitable controller bar or key; the 15 selecting mechanism of each member being itself controlled by a plurality of keys.

More particularly the invention relates to means in a machine of this class whereby the register may be quickly cleared of any 20 amount that may be registered thereon and the number bearing members restored to their zero position, that is, with the zero of each of the number bearing members in the reading position.

The invention has for one of its objects to provide an improved machine of this class having means adapted to be set, at will, for clearing the register and means for automatically rendering the clearing mechanism inactive when the register has been 35 thus cleared.

A further object is to provide an improved machine of this class having means for arresting the movement of the number 40 bearing members under the influence of the clearing mechanism whereby overthrow of the number bearing members will be prevented.

A further object is to provide an improved machine of this class which will be 45 simple and durable in construction, and effective and efficient in operation.

To the attainment of these ends and the accomplishment of other new and useful objects as will appear, the invention consists 50 in the features of novelty in substantially the construction, combination and arrangement of the several parts hereinafter more fully described and claimed and shown in

the accompanying drawings exemplifying 55 the invention, and in which—

Figure 1 is a vertical longitudinal sectional view of an improved machine of this class constructed in accordance with the principles of this invention. Fig. 2 is a 60 sectional view on line 2—2, Fig. 1. Fig. 3 is a sectional view on line 3—3, Fig. 1. Fig. 4 is an irregular sectional view taken on lines 4—4, Figs. 2 and 3, with parts omitted. Fig. 5 is a sectional view taken 65 on line 5—5, Fig. 1. Fig. 6 is a sectional view on line 6—6, Fig. 5. Fig. 7 is a detail sectional view on line 7—7, Fig. 6. Fig. 8 is a sectional view on line 8—8, Fig. 1. Fig. 9 is an enlarged detail plan view of a 70 portion of the carrying mechanism. Fig. 10 is a sectional view taken on lines 10—10, Figs. 2 and 3. Fig. 11 is a sectional view on line 11—11, Fig. 10. Fig. 12 is a sectional view on line 12—12, Fig. 10. Fig. 75 13 is a perspective view of a detail.

Referring more particularly to the drawings and in the present exemplification of the invention, the numeral 15 designates generally a supporting base upon which the 80 structure is mounted and rising from this base are a plurality of uprights 16, 17, 18, (see particularly Fig. 1), which uprights are spaced from each other. These uprights may be of any desired height and may be 85 connected by tie rods or bolts 19, 20, as shown. The upright 16 is preferably located some distance from the front wall of the machine and journaled in these uprights 16, 17, and 18 are a series of shafts 21, preferably 90 nine in number, and are arranged parallel with each other to extend longitudinally of the machine. The forward extremities of the shafts 21 project slightly beyond the upright 16 and secured to each 95 of these shafts is a bevel gear 22 with each of which a companion gear 23 on a shaft 24 meshes. This shaft 24 extends transversely with respect to the shafts 21 and is journaled in suitable bearings 25 (see particularly 100 Figs. 1 and 2) so that when the shaft 24 is rotated the shafts 22 will be correspondingly rotated. Secured to each of the shafts 21 is a mutilated drum 26 preferably 105 comprised of a series of mutilated gears, nine in number, arranged in close proximity to each other and these mutilated drums on the shafts 21 are arranged in staggered re-

lation with respect to each other and the gears of each series are provided with different numbers of teeth ranging gradually from 1 to 9. Journaled in the uprights 16, 17 and 18 and above each of the shafts 21 is another shaft 27 upon each of which is mounted a traveling gear 28. These gears 26, 28 constitute portions of selecting mechanisms for controlling the degree of rotation 10 of the number bearing members of the register and as the construction and operation of each of the selecting mechanisms is the same the specific description of one will apply equally to them all. The gear 28 is keyed 15 to the shaft 27 for rotation with the shaft and for adjustment longitudinally on the shaft and is provided with a recessed hub 29 into which recess a laterally projecting pin 30 on an arm 31 of a slide 32 projects. 20 (See particularly Figs. 1 and 3). The slide 32 is mounted in suitable bearings 33 and an elastic member 34 connected by one end to an arm 35 on the slide 32 and by its other end to a fixed support 36 is provided which 25 tends normally to move the slide 32 in a direction to move the traveling gear 28 into a position to mesh with the gear of the series 26 having but one tooth. The bearings 33 depend from a fixed portion 37 of the mechanism and the slide 32 is held against adjustment under the influence of the elastic member 34 by means of an arm 38 on a rock shaft 39. This rock shaft 39 is journaled in suitable bearings and is controlled by a 30 series of keys 40 so that when any one of the keys of the series is actuated, the shaft 39 will be rocked against the tension of an elastic member 40 to move the arm 38 out of the path of movement of the slide 32 and thereby release the slide to permit the latter to be moved under the influence of the elastic member 34 to adjust the traveling gear 28 with respect to the gear 26. The degree of movement of the slide 32 is controlled by 40 the respective keys 40. The specific construction and operation, however, of this portion of the mechanism forms no part of the present invention but constitutes the subject matter of another application. Suf- 45 fice it to say that the slide 30 and the stems of the keys 40 are so constructed that when one of the keys 40 is actuated, the gear 28 will be moved a distance corresponding to the key actuated and thereby position the gear 28 to mesh with the gear of the series 26 corresponding to that position. In this 50 position it will be manifest that a degree of rotation may be imparted to the shaft 27 corresponding to the number of teeth on the particular gear 26 with which gear 28 meshes, and inasmuch as the number bearing members 41 of the register are secured to the shafts 27 for rotation therewith, it 55 will be apparent that the rotation of shafts 27 will impart a corresponding degree of

rotation to their respective number bearing members 41 of the register.

Motion is imparted to the shafts 21 through the medium of the shaft 24 and this shaft 24 receives its rotation from a power shaft 42 (see Figs. 3 and 4), which latter shaft receives its motion from any suitable source. The shaft 42 may be a continuously rotating shaft, while the shafts 24 and 21 are intermittently rotated and in order to connect the latter shafts with the power shafts intermittently and to automatically release the shafts 21, 24, with respect to the power shaft 42 after the former shafts have made one complete rotation so that they will stop after this rotation, there is provided on the shaft 42 a star or toothed wheel 43 (shown more clearly in Figs. 3 and 4) which is secured to the shaft 42 for rotation therewith. Mounted loosely upon the shaft 42 is a disk 44 and pivotally supported by this disk is a dog or pawl 45 which co-operates with the star or toothed wheel 43 and an elastic member 46 tends normally to move the dog or pawl 45 in a direction to engage the star or toothed wheel 43 and thereby lock the disk 44 and a gear 46 which is carried by the disk 44 for rotation with the shaft 42. The gear 46 meshes with the gear 47 which is secured to and for rotation with a shaft 48. This shaft 48 is arranged parallel with the shaft 42 and is journaled in the uprights 17 and 16. Secured to the shaft 48 and for rotation therewith is a bevel gear 49 (see particularly Fig. 2) and this bevel gear 49 meshes with a companion gear 50 on the shaft 24. Thus it will be manifest that when the gear 46 is locked to the shaft 42 for rotation therewith, the gear 47 with which it meshes will also be rotated and as the gear 47 is secured to the shaft 48 for rotation therewith this shaft will be rotated as well as the shaft 24. The gear 46 is normally unlocked with respect to the shaft 42 and in order to accomplish this, there is provided another dog 51 (see Figs. 3 and 4) which is secured to a rock shaft 52 for rotation therewith and this shaft 52 is journaled in suitable bearings above and in proximity to the shaft 42 so that when the dog 50 is rocked in a manner to be set forth the shaft 52 will also be rocked. This dog 51 is adapted to be moved by means of an elastic member 53 in a direction to cause its shouldered extremity 54 to be normally moved into the path of movement of a shoulder 55 on the dog 45 so as to rock the latter about its point of pivotal support on the disk 44 against the tension of the elastic member 46 to unlock the gear 46 from the shaft 42. The dog 51 is adapted to be rocked to disengage the shoulder 55 of the dog 45 to release the latter by means of a controller bar or key, the stem 56 of which is shown in Fig. 4, and when the dog 125

45 is released, the elastic member 46 will move the dog 45 so that it will engage in the space between two of the teeth of the star or toothed wheel 43. The stem 56 of the controller bar or key is connected with a member designated generally by the reference numeral 57 which is loosely mounted upon the shaft 52. A member 58 is pivotally supported by the member 57 and is provided with a portion adapted to project over a shoulder 59 on the dog 51 and an elastic member 60 is provided which is connected with the member 58 and tends normally to move a portion thereof over the shoulder 59 of the dog 51 when the key stem 56 is elevated so that when the key stem is depressed the dog 51 will be rocked through the medium of the member 57 and the member 58. The key stem and the members 57, 58, may be returned in any suitable manner, preferably by means of an elastic member 61. It will thus be manifest that each time the key stem 56 is actuated, assuming the parts to be in the position shown in Fig. 4, the dog 51 will be actuated and the dog 45 released. When the key stem 56 is actuated a certain distance, the portion of the member 58 which projects over the shoulder 59 will pass off of the shoulder 55 and the dog 51 will be returned by the elastic member 61 so that its extremity 54 will be in a position to engage the shoulder 55 on the dog 45 to automatically unlock the gear 46 from the shaft 42.

35 After the completion of the calculation, and before another calculation can be made, it is necessary to return the slides 32 and the traveling gears 28 to release the actuated key and restore the parts to their normal positions. This is accomplished by means of a rocking member 62 (see Figs. 1 and 2) which is supported by arms 63 connected to a rock shaft 64 journaled in suitable supports and is so positioned that when the shaft 64 is rocked in one direction the member 62 will engage the depending portion or arm 35 on the slides 32 to move the latter against the tension of the elastic member 34, which latter, as has been before stated, is provided for shifting the member 32 longitudinally to move the gear 28 into a position to mesh with the gears 26. The shaft 64 is rocked at the completion of the calculation by means of a suitable connection between the shaft 48 and the shaft 56 which latter is arranged at right angles to the shaft 64. In order to thus rock the shaft 64, the shaft 56 is provided with an arm 65 (see Fig. 2) which co-operates with an arm 66 on the shaft 64. Any suitable connection is provided between the shafts 48 and 56 so that the latter will be operated intermittently. When the shaft 64 is rocked to return the slides 32 and the gears 28, tension is created upon an elastic member 67 (see Fig. 1) so that the

member 62 may be returned to its normal position or the position shown in Fig. 1 after the gears 28 and the slides 32 have been moved to their normal positions. In order to lock the shafts 27 against overthrow each is provided with any suitable mechanism such as a star or toothed wheel 68 (see Figs. 1 and 3), and a dog or pawl 69 which is pivotally mounted upon a suitable fixed support and adapted to co-operate with the wheel 68 when a cam 70, secured on shaft 21, moves the dog into the space between two of the teeth of the wheel 68. All of the above described parts, however, form no part of the present invention but constitute the subject matter of another pending application. Suffice it to say that by the actuation of one of the keys 40 the traveling gear 28 will be correspondingly set with relation to the gears 26 and after the controller bar or key is actuated to depress the stem 56 thereof, the power shaft 42 will be connected with the shaft 24 to rotate the shafts 21 thereby imparting motion to the gears 26, which latter impart variable movements to the shafts 27 and the corresponding number wheels 41, through the medium of the gears 28.

It is one of the primary objects of the present invention to provide mechanism for automatically clearing the number bearing members 41 of the register at will and in order to employ the same mechanism for clearing the number bearing members as is employed in calculation, suitable mechanism is provided which is adapted to be rendered inactive and active respectively when the calculation is being performed and when the clearing operation is being performed. Any suitable means may be provided for this purpose but a simple and efficient means embodies a gear 71 which is secured for rotation with each of the shafts 21. As the clearing mechanism for each of the number bearing members 41 is the same, the description of one will suffice. The gear 71 is secured to the shaft 21 preferably in close proximity to the number bearing member 41 and is provided preferably with nine teeth 72. Slidably mounted upon the shaft 27 is a sleeve 73 (see particularly Figs. 1, 6 and 7) to which sleeve is connected a gear 74. This gear is provided with nine teeth so arranged that a space 75 of some size will be formed between two of the teeth. This space 75 is so arranged with respect to the numbers 76 on the number bearing members 41 that when the zero of the number bearing member is in position to be read through the sight glass 77 in the top 78 of the casing, the space 75 will be disposed in proximity to the teeth 72 of the gear 71. This construction will permit the number bearing member 41 to remain in the zero position when the space 75 is adjacent the

periphery of the gear 71. This sleeve 73 is adapted to be moved longitudinally on the shaft 27 so that the gear 74 will be moved into a position to mesh with the gear 71 and into a position where it will not mesh with the gear 71. It will therefore be manifest that if the gear 74 is shifted on the shaft 27 into a position that it will mesh with the gear 71, the shaft 27 will be rotated when the shaft 21 is rotated inasmuch as the sleeve 73 is keyed to the shaft 27. Obviously when the gear 74 is moved into a position to mesh with the gear 71, the respective gears 28 must be in positions that they will not mesh with the coöperating gears 26.

Inasmuch as the direction of rotation of the number bearing members 41 is constant, both during the calculation and of the clearing operations, and inasmuch as the shaft 27 is rotated with some speed, it will be manifest that there might be a tendency to overthrow of the number bearing members 41 and in this event the number bearing members might not stop in the proper position when clearing, that is, with the zero in the reading position. In order to obviate this difficulty, there is provided in the present exemplification of this invention a pin or projection 79 (see Figs. 1 and 3) which projects from the hub 80 of the number bearing member 41. A member 81 is mounted for sliding movement, preferably upon spaced supports 83 (see particularly Fig. 3) which may be arranged adjacent the extreme number bearing members of the series. These supports 83 are secured to any fixed portion of the mechanism preferably the support 18, and elastic members 84, such as coil springs or the like, surround these supports and are disposed between the upright 18 and the member 81. Projecting laterally beyond the member 81 are a series of projections 85, one for each of the number bearing members 41 and are adapted to respectively coöperate with the pins or projections 79. The pins or projections 85 and the supports 83 are so constructed that the normal tendency of the elastic members 84 is to move the pins or projections 85 away from the pins or projections 79 and out of the path of the rotary movement of the latter. The gears 74 are preferably arranged in staggered relation with respect to each other so that some of the gears 74 will be disposed in close proximity to the member 81 and inasmuch as all of the gears 74 will be shifted on the shafts 27 each time the clearing mechanism is set, it will be manifest that the member 81 will also be shifted so as to move the pins or projections 85 into the path of movement of the pins or projections 79 of the number bearing members 41. In order that the mechanism may be arranged compactly as possible the member 81 may be provided

with a series of openings through which the shafts 27 project. The member 81 will have moved into a position to cause the pins 85 to project into the path of movement of the pins or projections 79 just as the gears 74 move into positions to mesh with the gears 71. When the parts are thus set, all that is necessary is to again actuate the controller bar or key to depress the stem 56 (see Fig. 4) to lock the gear 46 to the shaft 42. This will impart rotation to the shaft 24 in the manner already described and the shafts 21 will be correspondingly rotated. Under these conditions the rotary motion of the shaft 21 will then be imparted to the shafts 27 through the medium of the meshing gears 71, 74. When the number bearing members have reached their zero positions the pins 71 thereon will engage the respective pins or projections 85 on the member 81 and the number bearing members 41 will be arrested in their movement. After the number bearing members have been thus restored and the register cleared, all that is necessary is to shift the gears 74, the member 81 and the pins or projections 85 into the position shown in Fig. 1 when the machine will again be ready for calculation. The shifting of the gear 74 into and out of operating positions is accomplished in the present exemplification of the invention by manually actuated mechanism which will now be described.

Extending transversely of the shafts 21, preferably below the latter and adjacent the gears 71, is a rock shaft 86 (see Figs. 1, 3, 5, 10) journaled in suitable bearings and pivotally supported by this shaft are a series of yoke-shaped members designated generally by the reference numeral 87. One of these yoke-shaped members 87 is provided for each of the number bearing members 41 with the exception of the unit number bearing members, and comprises an arm 88 having a laterally projecting pin or lug 89, which latter projects into a circumferential recess 90 in the sleeve 73. An elastic member 91 is connected with each of the yokes 87 and also to a suitable fixed support. These elastic members 91 tend normally to move the gear 74 out of mesh with the gear 71 so that in order to move the gear 74 into a position that it will mesh with the gear 71, it is necessary to rock the yoke-shaped members 87 against the tension of these elastic members 91. This is accomplished by rocking the shaft 86, which latter is provided with a series of laterally projecting pins 92 (see Figs. 1 and 10), normally spaced a slight distance from the body portion of the yoke-shaped members, but in a position that when the shaft 86 is rocked in one direction, the pins will engage the yoke-shaped member to rock the latter and thereby shift the gear 74 through the medium of the arm 88. The

shaft 86 may be rocked by means of an arm or lever designated generally by the reference numeral 93 (see particularly Fig. 10), arranged in any convenient position for the operator, preferably adjacent the front of the machine. This lever 93 is pivotally mounted intermediate its ends as at 94 and is connected by means of a link 95 with an arm 96 on the shaft 86. The link 95 is provided with a pin and slot connection 97, 98, with the arm 96 for a purpose to be herein-after set forth. Thus it will be manifest that when the lever 93 is moved from the position shown in Fig. 10, forwardly, to rock the lever about its pivot 94, the link 95 will be shifted and this in turn will rock the shaft 86 through the medium of the arm 96 and the gear 74 will be positioned so as to mesh with the gear 71. In order to lock the parts in this adjusted position, any suitable mechanism may be provided, such for instance as a catch designated generally by the reference numeral 99 (see Fig. 10) which is pivoted intermediate its ends as at 100. One extremity 101 of this catch is provided with a shouldered portion adapted to coöperate with a shouldered portion 102 on the lever 93. An elastic member 103 is provided and tends normally to move the shouldered extremity 101 of the catch 99 in a direction to engage over the shoulder 102 when the lever is rocked and yields to permit the shoulder 102 to assume a position to be engaged by the shouldered portion 101. When the shaft 86 is thus rocked to position the gears 74 to mesh with the gears 71, tension will be created upon the elastic members 91 so that when the catch 99 is rocked to release the lever 93, the tension thus created upon the elastic members 91 will rock the shaft 86 in the opposite direction to move the gears 74 out of mesh with the gears 71. The catch 99 is adapted to be automatically rocked by means of a cam 104 (see Figs. 2 and 10) on the shaft 24 which is adapted to engage the extremity 105 of the catch at the completion of the revolution of the shaft 24.

The gear 74 of the units number bearing members (see Fig. 5) is adapted to be shifted by an arm 105 similar to the arms 88 of the yoke-shaped members 87, with the exception that the arm 105 is connected to the shaft 86 for movement therewith. This arm 105 is also provided with a laterally projecting portion 106 (see also Fig. 6) which projects into the circumferential recess 90 of the sleeve 73 so that when the shaft 86 is rocked in the manner already described, the gear 74 of the units number bearing member will be correspondingly shifted.

Mechanism whereby the carrying from one number bearing member to the next adjacent number bearing member of a higher denomination may be effected will now be described. Secured to each of the shafts 21 is a one-toothed gear 107 (see Figs. 1 and 8) which is preferably arranged in proximity with the respective gears 71 and a gear 108 is connected with each of the sleeves 73 and is adapted to be moved with the sleeve 73 when the latter is shifted. The gears 74, 108 are connected to the respective sleeves 73 in such a manner that they will be spaced from each other a distance less than the distance between the respective gears 71, 107, so that when the sleeve 73 is shifted in one direction or the other so as to cause one of the gears 74, 108, to be positioned so as to mesh with the respective gears 71, 107, the other of the gears 74, 108 will assume a position out of mesh with its respective gear on the shaft 21. In order to accomplish this the gears 71, 107 are so arranged that the sleeve 73 must be shifted in one direction, for instance, to the right as shown in Fig. 1 when the carrying operation is to take place, and to the left when the clearing operation is to take place. Inasmuch as the carrying operation is automatic, it is necessary that the sleeves 73 should be shifted on the respective shafts 27 independently with respect to each other and also independently with respect to the motion of the shaft 86. For this reason the yoke-shaped members 87 are provided, and are mounted loosely upon the shaft 86.

As has already been stated, the normal tendency of the elastic members 87 is to move the gear 74 out of mesh with respect to the gears 71 and as this movement of the gear 74 will shift the sleeve 73 to position the gear 108 so that it will mesh with the one-toothed gear 107, it will be manifest that mechanism must be provided for normally holding the gear 108 in a position that it will not mesh with the gear 107. At the same time, however, mechanism should be provided for releasing this gear 108 at the proper time when the carrying operation is to be effected. Suitable mechanism for accomplishing this comprises an arm 109 (see particularly Figs. 8 and 9) which is pivotally mounted upon any suitable fixed support 110, preferably the upright 17 and this arm 109 projects into the path of movement of the extremity 111 of the sleeve 73 and an elastic member 112 tends normally to move the arm 109 about its pivot 110 in a direction to engage the end of the sleeve 73 to hold the gear 108 in a position where it will not mesh with the gear 107 and to maintain the elastic member 87 under tension. A stop 109^a is provided for each of these arms 109 for limiting the movement of the latter under the influence of the elastic member 112. It will therefore be manifest that when the arm 109 is rocked to release the sleeve 73, the elastic member 91 will swing the yoke-shaped member 87 about its pivot to move 130

the gear 108 into a position to mesh with the gear 107. The arm 109 is rocked by means of a tooth 113 rotatable with the shaft 27 and which tooth engages an extension 114 of the arm. The tooth 113 is so arranged that when the number bearing member crosses the zero point, it will engage the extension 114 and rock the arm 109 against the tension of the elastic member 112. After the tooth 113 passes out of engagement with the extension 114 on the arm 109 the arm will be moved by the elastic member so that it will engage and rest upon the periphery of a portion of the sleeve 73.

After the completion of the calculation it is necessary to shift the gears 108 back to their original positions, that is, so that they will not be in mesh with the gears 107. This operation is effected by rocking the shaft 86 and in order to automatically rock the shaft, one of the shafts 21 is provided with a cam or tooth 115 (see Figs. 5 and 6) which is adapted to engage a lateral projection 116 on the shaft 86 to rock the latter against the tension of an elastic member 117. When the cam or projection 115 passes out of engagement with the projection 116 on a shaft 86, the tension of the elastic member 117 will restore the shaft 86 to its original position. When the shaft 86 is thus rocked, the pins or projections 92 thereon will move into engagement with the body portions of the yoke-shaped members 87 to rock the latter and thereby shift the sleeves 73 into such positions that the elastic members 112 will move the arms 109 behind the ends 111 of the sleeves 73 to hold the latter in position.

In order to lock the number bearing members 41 against accidental movement by the vibration of the machine or otherwise, when the cams 69 are moved out of locking position with respect to the star or toothed wheels 68 on the shafts 27, dogs 118 (see Figs. 1 and 3) are provided which coöperate with star or toothed wheels 119 on the shafts 27. As has already been stated, the gears 28 and the slides 32 are returned to their normal positions, that is, so that the gears 28 will not mesh with the gears 26, by the member 62, that is, by rocking the shaft 64. It is advisable that these gears 28 be shifted to their normal or inactive positions before the number bearing members or the register 55 is cleared. In order therefore to insure this position of the gears 28, the lever 93 is provided with a portion 120 (see Figs. 10 and 12) upon which is mounted an anti-friction roller 121. This roller 121 is so positioned that when the lever 93 is rocked about its pivot 94, the roller will engage one of the arms 63 and move the latter to rock the shaft 64 in a direction to cause the member 62 to engage the projecting portions 35 of the slides 32, to shift the latter and the respec-

tive gears 28 into their inoperating positions so that when the shafts 21 are set into motion after the clearing mechanism has been set, no damage will be caused to the mechanism. If desired, a guide 122 may be provided for the end of the lever 93. It has also been set forth that in order to connect the power shaft 42 with the shaft 44 and thereby impart rotation to the shaft 24 and the shafts 21, it is necessary to trip the dog 51 (see Fig. 4). This tripping of the dog 51 rocks the shaft 52 which rocking movement is effected through the medium of the members 57 and 58, in one direction. The shaft is rocked in the opposite direction by means of the elastic member 53.

In clearing the number bearing members it is first necessary to set the gears 74 by shifting the lever 93 (see Fig. 10) and in order that the parts may operate, these gears 71 must be actually set with respect to the gears 74. It will be manifest that unless these gears are thus properly set, before the actuation of the controller bar or key to trip the dog 51, the actuation of the latter might cause injury to the machine. In order therefore to positively insure the correct setting of the gear 74 and to prevent the actuation of the controller bar or key and the tripping of the dog 51 before the gears 74 are set, a suitable locking mechanism is provided which will now be described.

Extending transversely of the machine and at any convenient point, preferably adjacent the lever 93, (see Figs. 2, 4, 10, 11, 12 and 13) is a bar or rod 123 which is supported in any desired or suitable manner preferably by means of fastening devices 124 passing through slots 125 in the bar or rod 123. One extremity of this bar or rod 123 is bent or deflected downwardly as at 126 to extend into the path of movement of a pin or projection 127 on the shaft 52. The other extremity 128 of the bar or rod 123 is bent or deflected upwardly, as shown, and this upwardly deflected portion is preferably located in close proximity to the lever 93. A slide 129 is mounted upon any suitable fixed support and is provided with slots 130 through which fastening devices 131 pass. This slide 129 is provided with an arm 132 which is loosely connected as at 133 with the lever 93. The slide 129 is arranged transversely with respect to the bar or rod 123 and with one edge adjacent the upwardly deflected portion 128 of the bar or rod 123. This edge of the slide 129 is provided with recesses 134, 135, adapted to receive the upwardly deflected extremity 128 of the bar or rod 123, when the recesses are properly positioned with respect to such extremity. It will thus be manifest that when the lever 93 is shifted about its point of pivotal support 94, the slide 129 will be correspondingly shifted

and will be so moved that one or the other of the recesses 134, 135 will be in position to receive the extremity 128 of the bar or rod 123 when the lever 93 is in one or the 5 other of its proper positions, that is, to move the gear 74 either into or out of position to mesh with the gear 71. These recesses 134, 135, are spaced from each other and it will thus be manifest that unless the 10 slide 129 is properly shifted, the recesses 134, 135 will not be in position to receive the extremity 128 of the bar or rod 123. If the recesses are properly positioned with respect to the extremity 128, it will be manifest that 15 the shaft 52, (see Fig. 4), may be rocked in the manner already described and the dog 51 will then be shifted to release the dog 45. If the recesses 134, 135 are not in a proper position to receive the extremity 20 128 of the bar or rod 123, the shaft 52 cannot be rocked inasmuch as the pin or projection 127 will engage the depending portion 126 of the bar or rod 123 and any movement of the latter will cause the extremity 25 128 to engage the edge of the slide 129 and the shaft 52 will be held against movement. An elastic member 136 is provided and is connected to the bar or rod 123 and to a suitable fixed support and tends normally to 30 move the slide 123 in a direction to move the deflected extremity 128 out of the recesses 134, 135. It will therefore be manifest that unless the gears 74 are properly positioned with respect to the gears 71, when 35 it is desired to clear the machine, the controller bar or key cannot be actuated as the dog 51 will be locked against actuation.

The entire mechanism, with the exception of the extremity of the lever 93, the keys 40, 40 the stem 56 of the controller bar or key and the extremity of the power shaft 42, may be inclosed within the casing 137, as will be understood.

From the above description it is thought 45 that the operation of this machine will be clearly apparent but briefly stated, it is as follows: Assuming the parts to be in the position shown in Fig. 1 and with the number bearing members 41 in a zero position, 50 the operator by the actuation of one of the keys 40 of each series sets the selecting mechanism for controlling the degree of rotation of the respective number bearing members 41, by rocking the shaft 39 to release the sliding members 32. Thus released, the elastic members 34 will adjust the sliding members 32 and the gears 28 to move them into a position with respect to the gears 26, corresponding to the particular key actuated. Thus set, the controller bar or key 55 is actuated and this will shift the stem 56 (see Fig. 4) to rock the dog 51 and the shaft 52. This will release the dog 45 and the gear 46 will be locked to the power shaft 60 42. The rotary motion of the gear 46 will be imparted to the shaft 48 through the meshing gear 47 and motion of the shaft 48 will be imparted to the shaft 24 through the medium of the meshing gears 49, 50, (see Fig. 2). When the shaft 24 is rotated, 70 the shaft 21 will be rotated and the rotary motion of these shafts 21 will be imparted to the shaft 27 through the medium of the gears 26, 28. When the shaft 21 commences to rotate, the cams 70 will permit the dogs 75 69 to move out of locking position with the toothed wheel 68. The shafts 27 will rotate the number bearing members 41 and as the respective number bearing members cross the zero point, the teeth 113 (see Fig. 8) will 80 engage the extensions 114 on the respective arms 109 to shift the latter against the tension of the springs 112, thereby releasing the sleeves 73. Thus released, the elastic members 91 will shift the yoke-shaped members 87 to move the sleeves 73 in a direction to position the gears 108 so that they will mesh with the respective gears 107. After the completion of the calculation, the cam 115 on one of the shafts 21 (see Figs. 5 and 6) 85 90 will engage the projection 116 on the shaft 86 to rock the latter and thereby cause the pins or projections 92 thereon to engage the yoke-shaped members 87 to move the latter to shift the sleeve 73 and thereby move the 95 gears 108 into a position that they will not mesh with the gears 107. When the sleeves 73 are thus shifted, the elastic members 112 (see Fig. 8) will move the arms 109 behind the sleeves 73 and lock the sleeves and the 100 gears 108 in this position and will also maintain the springs 91 under tension. Just at the completion of the calculation, the shaft 64 will be rocked and the member 62 will engage the depending portion 35 on the 105 slides 32 to shift the latter and the gears 28 on the shafts 27 into their normal positions or out of mesh with the gears 26. This operation may be repeated as many times as desired. When it is desired to clear the 110 machine, that is, to remove the amount registered on the number bearing members 41, the lever 93 is shifted to rock the shaft 86 to cause the pins of projections 92 (see Fig. 10) thereon to shift the yoke-shaped members 87, and to rock the arm 105 (see Fig. 5) to move the sleeves 73 in a direction to position the gears 74 so that they will mesh with the respective gears 71. When the 115 gears 74 are properly positioned, the slide 129 (see Figs. 11 and 13) will have assumed a position that the recess 135 will be positioned to receive the extremity 128 of the bar or rod 123. Thus positioned, the stem 56 of the controller bar or key, (see 120 Fig. 4) may be actuated to rock the dog 51 and the shaft 52 so as to release the dog 45 and thereby connect the power shaft with the mechanism so that the shafts 21 will be 125 rotated and the shafts 27 will then be ro- 130

tated through the medium of the gears 71, 74. When the respective number bearing members reach the zero position, that is, with the zero in reading position, the space 75 on the gears 74 will be adjacent the teeth of the gears 71, so that the respective gears 71 will not move the gears 74. When the gears 74 are positioned to mesh with the gears 71, the member 81 will be adjusted to 10 project the pins 85 into the path of movement of the pins 79 on the number bearing members 41. When the space 75 is in proximity to the teeth of the gears 71 the pins 79 will engage the pins 85 on the member 81 and the number bearing member 41 will be arrested in its movement and held against overthrow. After the machine has been thus cleared the lever 93 may be shifted in the opposite direction about its pivot, to 15 move the gears 74 out of mesh with the gears 71 and when the gears 74 have been properly positioned by this movement of the lever 93, the other recess 134 of the slide 129 will be in a position to receive the 20 tremity 128 of the bar or rod 123 to permit the machine to be operated for calculation. Before the lever 93 can be shifted to throw the clearing mechanism out of operation, the catch 99 must be tripped and this is 25 accomplished by means of the cam 104 (see Fig. 10) on the shaft 24, which is arranged to operate upon the catch 99 just at the completion of the revolution of the shaft 24.

What is claimed as new is—

30 1. In a machine of the class described, the combination of a register embodying rotatable number bearing members, means for actuating the same to register amounts thereon, means adapted to be set to also 35 operate the members to clear the latter of such amounts, and means adapted to be set by the last said means for controlling the degree of movement of the members by the said clearing mechanism.

40 2. In a machine of the class described, the combination of a registry embodying rotatable number bearing members, means for rotating the same to register amounts thereon, means for also rotating the members in 45 the same direction as they are rotated to register, to clear them of such amounts, and means adapted to be set to arrest the movement of the said members by the said clearing mechanism.

50 3. In a machine of the class described, the combination of a register embodying rotatable number bearing members, means for rotating the same to register amounts thereon, means for also rotating the members in 55 the same direction in which they are rotated to register, to clear them of such amounts, and a stop adapted to be set to arrest the movement of the said members by the said clearing mechanism.

60 4. In a machine of the class described,

the combination of a register embodying rotatable number bearing members rotatable in one direction only, means for rotating the same to register amounts thereon, means for also rotating the members to 70 clear them of such amounts, and means adapted to be set to arrest the movement of the said members by the said clearing mechanism.

5. In a machine of the class described, 75 the combination of a register embodying rotatable number bearing members having a constant direction of rotation, mechanism for imparting variable movements to said members to register amounts thereon, mechanism operatively connected with the first recited mechanism and adapted to be set to actuate said members to clear the latter of such amounts, and means for locking the second recited mechanism in its set position. 80

6. In a machine of the class described, the combination of a register embodying rotatable number bearing members having a constant direction of rotation, mechanism for imparting variable movements to said members to register amounts thereon, mechanism operatively connected with the first recited mechanism and adapted to be set to actuate said members to clear the latter of such amounts, means for locking the second 90 recited mechanism in its set position, and means for releasing the latter. 95

7. In a machine of the class described, the combination of a register embodying rotatable number bearing members having 100 a constant direction of rotation, mechanism for imparting variable movements to said members to register amounts thereon, mechanism operatively connected with the first recited mechanism and adapted to be set 105 to actuate said members to clear the latter of such amounts, means for locking the second recited mechanism in its set position, and means for automatically releasing the latter. 110

8. In a machine of the class described, the combination of a register embodying rotatable number bearing members rotatable in one direction only, mechanism for imparting variable movement to the members 115 to register amounts thereon, mechanism adapted to be set for also imparting rotation to said members for clearing them of such amounts, and means controlled by the last recited mechanism and adapted to be set to limit the movement imparted to the said members by the second recited mechanism. 120

9. In a machine of the class described, the combination of a register embodying 125 rotatable number bearing members rotatable in one direction only, mechanism for imparting variable movement to the members to register amounts thereon, mechanism adapted to be set for also imparting rota- 130

tion to said members for clearing them of such amounts, and means operating in unison with the last recited mechanism and adapted to be set to limit the movement imparted to the said members by the second recited mechanism.

10. In a machine of the class described, the combination of a register embodying rotatable number bearing members rotatable in one direction only, mechanism for imparting variable movement to the members to register amounts thereon, mechanism adapted to be set for also imparting rotation to said members for clearing them of such amounts, and stops adapted to be set by the setting of the last recited mechanism and with which the number bearing members coöperate whereby the members will be arrested in their movement by the second recited mechanism.

11. In a machine of the class described, the combination of a register embodying rotatable number bearing members rotatable in one direction only, mechanism for imparting variable movement to the members to register amounts thereon, mechanism adapted to be set for also imparting rotation to said members for clearing them of such amounts, and means adapted to be set by the setting of the last recited mechanism and with which means the number bearing members coöperate, whereby the members will be arrested in their movement by the second recited mechanism when the members reach predetermined positions.

12. In a machine of the class described, the combination of a register embodying rotatable number bearing members, means for rotating said members to register amounts thereon, means for also rotating the members in the same direction in which they are rotated for registering, to clear them of such amounts, and means for preventing overthrow of the members when actuated by the second recited means.

13. In a machine of the class described, the combination of a register embodying rotatable number bearing members having a constant direction of rotation, means for rotating said members to register amounts thereon, means for also rotating the members in the same direction in which they are rotated for registering to clear them of such amounts, and means for preventing overthrow of the members when actuated by the second recited means.

14. In a machine of the class described, the combination of a register embodying rotatable number bearing members, means for actuating the same to register amounts thereon, means adapted to be set to also actuate said members to clear the latter of such amounts, means for rendering the second recited means inactive when the number bearing members assume predetermined po-

sitions, and means for preventing overthrow of the said members when actuated by the second recited means.

15. In a machine of the class described, the combination of a register embodying rotatable number bearing members having a constant direction of rotation, means for actuating the same to register amounts thereon, means adapted to be set to also actuate said members to clear the latter of such amounts, means for rendering the second recited means inactive when the number bearing members assume predetermined positions, and means for preventing overthrow of the said members when actuated by the second recited means.

16. In a machine of the class described, the combination of a register embodying rotatable number bearing members, means for actuating the same to register amounts thereon, means adapted to be set to also actuate said members to clear the latter of such amounts, means for rendering the second recited means inactive when the number bearing members assume predetermined positions, and means embodying a stop movable into and out of operating position for preventing overthrow of the said members when actuated by the second recited means.

17. In a machine of the class described, the combination of a register embodying rotatable number bearing members, means for actuating the same to register amounts thereon, means adapted to be set to also actuate said members to clear the latter of such amounts, means for rendering the second recited means inactive when the number bearing members assume predetermined positions, means embodying a stop movable into operating position for preventing overthrow of the members when actuated by the second recited means, and means tending normally to move the stop out of operating position.

18. In a machine of the class described, the combination of a register embodying rotatable number bearing members, means for actuating the same to register amounts thereon, means adapted to be set to also actuate said members to clear the latter of such amounts, means for rendering the second recited means inactive when the number bearing members assume predetermined positions, a stop for preventing overthrow of the number bearing members when actuated by the second recited means, and means tending normally to move the stop out of operating position, said stop adapted to be rendered active against the tension of the last recited means by the setting of the second recited means.

19. In a machine of the class described, the combination of a driving and a driven element, a rotatable number bearing member connected with the driven element for rota-

tion therewith, means for connecting said elements for rotating the number bearing member to add amounts thereon, means for controlling the last said means, additional means for connecting the said elements for operating the number bearing member to clear the same of such amounts, and means for controlling the last said means at will.

20. In a machine of the class described, 10 the combination of a driving and a driven element, a rotatable number bearing member connected with the driven element for rotation therewith and having a constant direction of rotation, means for connecting said elements for rotating the number bearing member to add amounts thereon, means for controlling the last said means, additional means for connecting the said elements for operating the number bearing member to 15 clear the same of such amounts, and means for controlling the last said means at will.

21. In a machine of the class described, 20 the combination of a driving and a driven element, a rotatable number bearing member connected with the driven element for rotation therewith, means for connecting said elements for rotating the number bearing member to add amounts thereon, means for controlling the last said means, additional means for connecting the said elements for operating the number bearing member to clear the same of such amounts, 25 means for controlling the last said means at will, and means whereby the last recited connecting means will be rendered inactive automatically when the said number bearing member assumes a predetermined position.

22. In a machine of the class described, 30 the combination of a driving and a driven element, a rotatable number bearing member connected with the driven element for rotation therewith, means for connecting said elements for rotating the number bearing member to add amounts thereon, means for controlling the last said means, additional means for connecting the said elements for operating the number bearing members to clear the same of such amounts, 35 means for controlling the last said means at will, means whereby the last recited connecting means will be rendered inactive automatically when the number bearing member assumes a predetermined position, and means for preventing overthrow of the number bearing member when the last recited connecting means is rendered inactive.

23. In a machine of the class described, 40 the combination of a driving and a driven element, a rotatable number bearing member connected with the driven element for rotation therewith, means for connecting said elements for rotating the number bearing member to add amounts thereon, means for controlling the last said means, additional 45 means for connecting the said elements for

operating the number bearing members to clear the same of such amounts; means for controlling the last said means at will, means whereby the last recited connecting means will be rendered inactive automatically when the number bearing member assumes a predetermined position, and means for preventing overthrow of the number bearing member when the last recited connecting means is rendered inactive, said 70 overthrow preventing means embodying a stop controlled by the second recited connecting means.

24. In a machine of the class described, 75 the combination of a driving and a driven element, a rotatable number bearing member connected with the driven element for rotation therewith, means for connecting said elements for rotating the number bearing member to add amounts thereon, means for controlling the last said means, additional means for connecting the said elements for operating the number bearing members to clear the same of such amounts, 80 means for controlling the last said means at will, means whereby the last recited connecting means will be rendered inactive automatically when the number bearing member assumes a predetermined position, and means for preventing overthrow of the 85 number bearing member when the last recited connecting means is rendered inactive, said overthrow preventing means embodying a normally inactive stop adapted to be rendered active when the second recited connecting means is rendered active.

25. In a machine of the class described, 90 the combination of a driving and a driven element, a rotatable number bearing member connected with the driven element for rotation therewith, means for connecting said elements for rotating the number bearing member to add amounts thereon, means for controlling the last said means, additional means for connecting the said elements for operating the number bearing members to clear the same of such amounts, 95 means for controlling the last said means at will, means whereby the last recited connecting means will be rendered inactive automatically when the number bearing member assumes a predetermined position, and means for preventing overthrow of the number bearing member when the last recited connecting means is rendered inactive, said 100 overthrow preventing means embodying a normally inactive stop adapted to be rendered active when the second recited connecting means is rendered active.

26. In a machine of the class described, 105 the combination of a driving and a driven element, a rotatable number bearing member connected with the driven element for rotation therewith, means for connecting said elements for rotating the number bearing member to add amounts thereon, means for controlling the last said means, additional means for connecting the said elements for operating the number bearing members to clear the same of such amounts, 110 means for controlling the last said means at will, means whereby the last recited connecting means will be rendered inactive automatically when the number bearing member assumes a predetermined position, and means for preventing overthrow of the number bearing member when the last recited connecting means is rendered inactive, said 115 overthrow preventing means embodying a stop adapted to be rendered active and inactive by the second recited connecting means when the latter is rendered active and inactive respectively.

27. In a machine of the class described, 120 the combination of a driving and a driven element, a rotatable number bearing member connected with the driven element for rotation therewith, means for connecting said 125 elements for rotating the number bearing member to add amounts thereon, means for controlling the last said means, additional means for connecting the said elements for

- elements for rotating the number bearing member to add amounts thereon, means for controlling the last said means, additional means for connecting the said elements for 5 operating the number bearing members to clear the same of such amounts, means for controlling the last said means at will, means whereby the last recited connecting means will be rendered inactive automatically 10 when the number bearing member assumes a predetermined position, means for preventing overthrow of the number bearing member when the last recited connecting means is rendered inactive, said overthrow 15 preventing means embodying a stop adapted to be rendered active and inactive by the second recited connecting means when the latter is rendered active and inactive respectively, and means for locking the stop 20 and the second recited connecting means in active positions.
27. In a machine of the class described, the combination of a driving and a driven element, a rotatable number bearing member 25 connected with the driven element for rotation therewith, means for connecting said elements for rotating the number bearing member to add amounts thereon, means for controlling the last said means, additional 30 means for connecting the said elements for operating the number bearing members to clear the same of such amounts, means for controlling the last said means at will, means whereby the last recited connecting 35 means will be rendered inactive automatically when the number bearing member assumes a predetermined position, means for preventing overthrow of the number bearing member when the last recited connecting 40 means is rendered inactive, said overthrow preventing means embodying a stop adapted to be rendered active and inactive by the second recited connecting means when the latter is rendered active and inactive respectively, means for locking the stop and the second recited connecting means in active positions, and means for automatically 45 unlocking the locked parts.
28. In a machine of the class described, 50 the combination of a driving and a driven element, a number bearing member having a constant direction of movement and connected with the driven element for rotation therewith, means adapted to connect the said elements to operate the number bearing member to register amounts thereon, additional means adapted to connect said elements to operate the number bearing member to clear the latter of such amounts, the 55 last said means embodying coöperating gears having relative lateral movement, and means for imparting such relative movement to the gears to render said connection operative and inoperative at will.
- 60 29. In a machine of the class described, 65 the combination of a driving and a driven element, a number bearing member having a constant direction of movement and connected with the driven element for rotation therewith, means adapted to connect the said
- the combination of a driving and a driven element, a number bearing member having a constant direction of movement and connected with the driven element for rotation therewith, means adapted to connect the said 70 elements to operate the number bearing member to register amounts thereon, additional means adapted to connect said elements to operate the number bearing member to clear the latter of such amounts, the 75 last said means embodying coöperating gears having relative lateral movement, means for imparting such relative movement to the gears to render said connection operative and inoperative at will, and means controlled by the relative movement of the gears for preventing overthrow of the number bearing member.
30. In a machine of the class described, the combination of a driving and a driven 80 element, a number bearing member having a constant direction of movement and connected with the driven element for rotation therewith, means adapted to connect the said elements to operate the number bearing 85 member to register amounts thereon, additional means adapted to connect said elements to operate the number bearing member to clear the latter of such amounts, the last said means embodying coöperating gears 90 having relative lateral movement, means for imparting such relative movement to the gears to place them in and out of position to mesh, and means for disconnecting said gears when the number bearing member assumes a predetermined position and while 95 the gears are in position to mesh.
31. In a machine of the class described, the combination of a driving and a driven 100 element, a number bearing member having a constant direction of movement and connected with the driven element for rotation therewith, means adapted to connect the said elements to operate the number bearing 105 member to register amounts thereon, additional means adapted to connect said elements to operate the number bearing member to clear the latter of such amounts, the last said means embodying coöperating gears 110 having relative lateral movement, means for imparting such relative movement to the gears to place them in and out of position to mesh, means for disconnecting said gears when the number bearing member assumes a predetermined position and while 115 the gears are in position to mesh, and means for preventing overthrow of the number bearing member when the gears are thus disconnected.
32. In a machine of the class described, 120 the combination of a driving and a driven element, a number bearing member having a constant direction of movement and connected with the driven element for rotation therewith, means adapted to connect the said 125
- 130

elements to operate the number bearing member to register amounts thereon, additional means adapted to connect said elements to operate the number bearing member to clear the latter of such amounts, the last said means embodying coöperating gears having relative lateral movement, means for imparting such relative movement to the gears to place them in and out of position to mesh, means for disconnecting said gears when the number bearing member assumes a predetermined position and while the gears are in position to mesh, and means controlled by the relative movement of the gears for preventing overthrow of the number bearing members when the gears are thus disconnected.

33. In a machine of the class described, the combination of a driving and a driven element, a number bearing member having a constant direction of movement and connected with the driven element for rotation therewith, means adapted to connect the said elements to operate the number bearing member to register amounts thereon, additional means adapted to connect said elements to operate the number bearing member to clear the latter of such amounts, the last said means embodying coöperating gears having relative lateral movement, means for imparting such relative movement to the gears to place them in and out of position to mesh, means for disconnecting said gears when the number bearing member assumes a predetermined position and while the gears are in position to mesh, and a stop adapted to be set by the relative movement of the gears for preventing overthrow of the number bearing member when the gears are thus disconnected.

34. In a machine of the class described, the combination of a driving and a driven element, a number bearing member having a constant direction of rotation, connected with the driven element for rotation thereby, means connecting the elements for rotating the number bearing member to register amounts thereon, additional means for connecting the elements to rotate the number bearing member to clear the latter of such amounts, the last recited means embodying coöperating gears movable into and out of position to mesh, and means for thus moving the gears, one of said gears being mutilated whereby the gears will be rendered inactive when the number bearing member reaches a predetermined position.

35. In a machine of the class described, the combination of a driving and a driven element, a number bearing member having a constant direction of rotation, connected with the driven element for rotation thereby, means connecting the elements for rotating the number bearing member to register amounts thereon, additional means for

connecting the elements to rotate the number bearing member to clear the latter of such amounts, the last recited means embodying coöperating gears movable into and out of position to mesh, and means for thus moving the gears, one of said gears being provided with a mutilated portion whereby the gears will be rendered inactive when the number bearing member reaches a predetermined position, and while the gears are in position to mesh.

36. In a machine of the class described, the combination of a driving and a driven element, a number bearing member having a constant direction of rotation, connected with the driven element for rotation thereby, means connecting the elements for rotating the number bearing member to register amounts thereon, additional means for connecting the elements to rotate the number bearing member to clear the latter of such amounts, the last recited means embodying coöperating gears movable into and out of position to mesh, means for thus moving the gears, one of said gears being provided with a mutilated portion whereby the gears will be rendered inactive when the number bearing member reaches a predetermined position, and means for preventing overthrow of the number bearing member when the gears are thus rendered inactive.

37. In a machine of the class described, the combination of a driving and a driven element, a number bearing member having a constant direction of rotation, connected with the driven element for rotation thereby, means connecting the elements for rotating the number bearing member to register amounts thereon, additional means for connecting the elements to rotate the number bearing member to clear the latter of such amounts, the last recited means embodying coöperating gears movable into and out of position to mesh, means for thus moving the gears, one of said gears being provided with a mutilated portion whereby the gears will be rendered inactive when the number bearing member reaches a predetermined position, a stop carried with the number bearing member and a stop controlled by the movement of the gears into and out of meshing position and coöperating with the first recited stop to prevent overthrow of the number bearing member.

38. In a machine of the class described, the combination of a driving and a driven element, a register embodying a rotatable number bearing member connected with the driven element for rotation thereby and having a constant direction of rotation, means for connecting said elements to rotate the number bearing member to register amounts thereon, additional means connecting said elements to rotate the number bear-

ing member to clear the latter of such amounts, the last recited means embodying coöperating gears adapted for relative lateral movement, means for imparting such 5 relative movement to place the gears in position to mesh, means for locking the parts in such position, power means for imparting motion to the driving element, and means controlled by the power mechanism 10 for automatically unlocking the parts.

39. In a machine of the class described, the combination of a driving and a driven element, a register embodying a rotatable number bearing member connected with the 15 driven element for rotation thereby and having a constant direction of rotation, means for connecting said elements to rotate the number bearing member to register amounts thereon, additional means connecting said elements to rotate the number bearing member to clear the latter of such amounts, the last recited means embodying coöperating gears adapted for relative lateral movement, means for imparting such 20 relative movement to place the gears in position to mesh, means for locking the parts in such position, power means for imparting motion to the driving element, means for rendering the gears inactive while 25 in meshing position when the number bearing member assumes a predetermined position, and means controlled by the power mechanism for automatically unlocking the parts.

35 40. In a machine of the class described, the combination of a driving and a driven element, a register embodying a rotatable number bearing member connected with the driven element for rotation thereby and having a constant direction of rotation, means for connecting said elements to rotate the number bearing member to register amounts thereon, additional means connecting said elements to rotate the number bearing member to clear the latter of such amounts, the last recited means embodying coöperating gears adapted for relative lateral movement, means for imparting such 45 relative movement to place the gears in position to mesh, means for locking the parts in such position, power means for imparting motion to the driving element, means for rendering the gears inactive while in meshing position when the number bearing 50 member assumes a predetermined position, means for preventing overthrow of the number bearing member when the gears are thus rendered inactive, and means, controlled by the power mechanism for automatically unlocking the parts.

41. In a machine of the class described, the combination of a register embodying a rotatable number bearing member having a constant direction of rotation, operating 65 mechanism therefor for registering amounts

thereon, means adapted to be set to operate the said member to clear the same of such amounts, means embodying a lever for setting such parts, a catch coöperating with the lever for locking the parts in set position, power mechanism for imparting motion to the said operating mechanism and a cam operating in unison with the said operating mechanism for automatically tripping the catch.

42. In a machine of the class described, the combination of a register embodying a rotatable number bearing member having a constant direction of rotation, operating mechanism therefor for registering amounts 70 thereon and embodying selecting mechanism adapted to be set for imparting variable movement to the member and keys for setting said mechanism, means adapted to be set to clear the said member of such amounts, means embodying a lever for setting the last recited means, and means controlled by said lever for restoring the said selecting mechanism.

43. In a machine of the class described, the combination of a register embodying a rotatable number bearing member having a constant direction of rotation, operating mechanism therefor for registering amounts 75 thereon and embodying selecting mechanism 80 adapted to be set for imparting variable movement to the member and keys for setting said mechanism, means adapted to be set to clear the said member of such amounts, means embodying a lever for setting the last recited means, means controlled by said lever for restoring the said selecting mechanism, power mechanism, a normally inactive connection between the power and the said operating mechanism, means for 85 controlling the connection, and means for preventing actuation of the last said means until the first recited means is properly set.

44. In a machine of the class described, the combination of a register embodying a 90 rotatable number bearing member having a constant direction of rotation, operating mechanism therefor for registering amounts thereon and embodying selecting mechanism 95 adapted to be set for imparting variable movement to the member and keys for setting said mechanism, means adapted to be set to clear the said member of such amounts, means embodying a lever for setting the last recited means, means controlled 100 by said lever for restoring the said selecting mechanism, power mechanism, a normally inactive connection between the power and the said operating mechanism, means for 105 controlling the connection, and means for preventing actuation of the last said means until the first recited means is properly set.

45. In a machine of the class described, the combination of a register embodying a 110

rotatable number bearing member having a constant direction of rotation, operating mechanism therefor for registering amounts thereon and embodying selecting mechanism 5 adapted to be set for imparting variable movement to the member and keys for setting said mechanism, means adapted to be set to clear the said member of such amounts, means embodying a lever for setting the last recited means, means controlled by said lever for restoring the said selecting mechanism, power mechanism, a normally inactive connection between the power and the said operating mechanism, means for 10 controlling the connection, and means for locking the last said means against actuation until the first said means is properly set, said locking means embodying a shoul- 15 dered element and a slide provided with a recess to receive said shoulder, said slide being movable to displace the recess with respect to the said shoulder.

46. In a machine of the class described, the combination of a register embodying a 25 rotatable number bearing member having a constant direction of rotation, operating mechanism therefor for registering amounts thereon and embodying selecting mecha-

nism adapted to be set for imparting variable movement to the member and keys for 30 setting said mechanism, means adapted to be set to clear the said member of such amounts, means embodying a lever for setting the last recited means, means controlled by said lever for restoring the said 35 selecting mechanism, power mechanism, a normally inactive connection between the power and the said operating mechanism, means for controlling the connection, and means for locking the last said means 40 against actuation until the first said means is properly set, said locking means embodying a shouldered element and a slide provided with a recess to receive said shoulder, said slide being operatively connected with 45 the lever and movable thereby to displace the recess with respect to the said shoulder.

In testimony whereof I have signed my name to this specification, in the presence of two subscribing witnesses, on this 7th day of July, A. D. 1911.

OTTO MALCHER.
